UNITED STATES PATENT OFFICE.

RAFFAELE BACCELLIERI, OF PHILADELPHIA, PENNSYLVANIA.

RATCHET MECHANISM.

Application filed April 12, 1924. Serial No. 706,095.

To all whom it may concern:

Be it known that I, RAFFAELE BACCELLIERI, a citizen of the United States, residing at Philadelphia, in the county of Philadelphia and State of Pennsylvania, have invented certain new and useful Improvements in Ratchet Mechanism, of which the following is a specification.

My invention relates to ratchet mechanism for fruit presses.

In a ratchet mechanism having a horizontally pivoted arm carrying a vertically slidable pawl, the arm wears at the pivot to a loose fit. This allows the arm to swing vertically in the direction of the sliding pawl. When horizontal stress is placed on the arm to actuate the ratchet wheel, the pawl and arm, being resisted in their horizontal movement by the ratchet wheel and free to move vertically by the loose fit at the pivot, move in a vertical direction. This action causes the pawl to slip out of its hole in the ratchet wheel. When the ratchet mechanism is worn to such extent that the pawl, instead of taking a hold when within a hole in the ratchet wheel, slips out of the hole, it is useless and practically beyond repair.

The objects of my invention are to provide means on a ratchet mechanism which will keep the actuating arm and its pawl in proper position for taking hold of the ratchet wheel at all times regardless of the wear or loose fit at its pivot, and to provide a ratchet mechanism which may be readily cast and requires practically no machining.

These objects, and other advantageous ends which will be described hereinafter, I attain in the following manner, reference being had to the accompanying drawings in which—

Figure 1 is a side elevation of a fruit press partly in section having my invention applied thereto,

Figure 2 a plan view of my invention,

Figure 3 a section on line 3—3 of Figure 2,

Figure 4 a section on line 4—4 of Figure 2, and

Figure 5 a fragmentary section on line 5—5 of Figure 2.

Referring to the drawings, 1 indicates a base having a counter-bore 2 which forms a shoulder 3. A ratchet wheel 4 has the lower end 5 of its hub rotatably mounted within the bore and resting on shoulder 3. If de-

sired, a thrust ball or roller bearing may be interposed between the end 5 and shoulder 3. The upper end 6 of the hub has an annular groove 7. A head 8 is pivoted to the base at 9 and has an actuating arm 10 pivoted thereto at 11. The actuating arm is of the yoke type and has pawls 12 slidable in the ends of the yoke. The pawls are adapted to engage within any of the holes 13 spaced around the ratchet wheel. For the purpose of increasing the speed of rotation when the resisting torque of the ratchet wheel is small, I provide holes 14 spaced around the wheel nearer to its center than the holes 13. Pawls 12 may be inserted in guideways 15 to engage within the holes 14. Arm 10 is provided with guides 16 embracing the inner wall of and sliding within annular groove 7 to hold the arm against movement in the direction of the axis of the ratchet wheel. The hub of the ratchet wheel is threaded as shown at 17 and receives a screw 18 secured to a support 19 of an ordinary fruit press. A cage 20 rests on the support and surrounds the screw. Pressure blocks 21 are adapted to move within the cage to press the fruit therein. Base 1 is forced down against the blocks 21 by the threaded hub of the ratchet wheel.

To actuate my improved ratchet mechanism for pressing fruit, a handle 22 is connected to head 8 and oscillated to move arm 10 over the holes in the ratchet wheel. When the arm moves in one direction one of the pawls engages within a hole and moves the ratchet wheel and the other pawl slides out of a hole. When the arm is moved in the opposite direction the first pawl slides out of a hole and the second pawl engages within a hole, and moves the ratchet wheel, thus reciprocating movement of arm 10 will impart rotary movement to ratchet wheel 4.

When it is desired to move the ratchet wheel at a greater speed, pawls 12 are placed within guideways 15 and the mechanism actuated as before, the pawls engaging within and sliding out of holes 14 which are nearer to the center of the ratchet wheel.

Annular groove 7 co-operating with guides 16 prevents arm 10 from swinging upward and keeps the arm in proper position over the ratchet wheel so that the pawls will engage within the holes. The ratchet mechanism requires comparatively little machining because arm 10 holds the ratchet wheel in the counterbore, and the annular

groove 8 and pivot 11 hold the arm in proper position on the ratchet wheel so that no accurate fit is required between the moving parts. This allows the parts to be used as 5 cast. It is not essential that the pivots 9 and 11 fit accurately within their holes, because the arm is held in proper position by guides 16 and groove 7.

While I have described my invention as 10 taking a particular form, it will be understood that the various parts may be changed without departing from the spirit thereof, and hence I do not limit myself to the precise construction set forth, but consider that 15 I am at liberty to make such changes and alterations as fairly come within the scope of the appended claims.

Having thus described my invention, what 20 I claim as new and desire to secure by Letters Patent is:—

1. In a ratchet mechanism, a ratchet wheel; an arm movable transversely to the axis of the wheel; a pawl slideable in the arm in the direction of the axis of the wheel and 25 adapted to engage and move the wheel, and means for holding the arm against movement in the direction of the axis of the wheel.

2. In a ratchet mechanism, a ratchet 30 wheel; an arm movable transversely to the axis of the wheel; a pawl slideable in the arm in the direction of the axis of the wheel and adapted to engage and move the wheel, and means on the wheel for holding the arm 35 against movement in the direction of the axis of the wheel.

3. In a ratchet mechanism, a ratchet 40 wheel having an annular groove; an arm movable within the groove transversely to its axis, and a pawl slideable in the arm in the direction of the axis of the wheel and adapted to engage and move the wheel.

4. In a ratchet mechanism, a base having

a counter-bore; a ratchet wheel having one 45 end of its hub rotatable in the bore and the other end provided with an annular groove; an arm movable within the groove transversely to the axis of the wheel; a pawl slideable in the arm in the direction of the axis of the wheel and adapted to engage and move the wheel, and means on the base for moving the arm.

5. In a ratchet mechanism, a ratchet wheel 50 having an annular groove; a yoked arm provided with guides movable within the groove transversely to its axis, and a pawl slideable in the arm in the direction of the axis of the wheel and adapted to engage and move the wheel.

6. In a ratchet mechanism, a base having 55 a counterbore; a ratchet wheel having one end of its hub rotatable in the bore and the other end provided with an annular groove; a yoked arm provided with guides movable within the groove transversely to the axis of the wheel; a pawl slideable in the arm in the direction of the axis of the wheel and adapted to engage and move the wheel, and a head pivoted to the base and the arm.

7. In a ratchet mechanism, a ratchet wheel 60 having annular rows of spaced holes at different distances from its center, and an annular groove in its hub; a yoked arm provided with guides movable within the groove transversely to its axis, and pawls adapted to slide within the ends of the arm into engagement with either of the rows of holes to move the ratchet wheel.

In testimony whereof I have signed my 65 name to this specification in the presence of two subscribing witnesses.

RAFFAELE BACCELLIERI.
